(57) **CLAIM**

The ornamental design for a combination of a base phone, a smart phone, and a cover, as shown and described.

DESCRIPTION

FIG. 1 is a front view of an article that includes a combination of a base phone, a smart phone, and a cover, showing my new design;

FIG. 2 is a front view of the article of FIG. 1, in which the smart phone is partially slid out of a pocket of the cover and a strap for the pocket is folded behind the smart phone;

FIG. 3 is a side view of the article of FIG. 1;

FIG. 4 is a rear view of the article of FIG. 1, showing the base phone exposed at a rear of the cover;

FIG. 5 is a bottom view of the article of FIG. 1; and,

FIG. 6 is a front view of the article of FIG. 1, in which the base phone and the smart phone are omitted.

The base phone and the smartphone are shown omitted from FIG. 6 for illustrative purposes only.

The wave indicator in FIGS. 1-4 illustrates the bounds of the claim.

The broken lines on the cover illustrate claimed stitching.
